ALMON W. CURTIS, OF CORTLAND, NEW YORK.

FOLDING TOP FOR VEHICLES.

1,403,738.

Specification of Letters Patent. Patented Jan. 17, 1922.

Application filed March 24, 1919. Serial No. 284,608.

To all whom it may concern:

Be it known that I, ALMON W. CURTIS, a citizen of the United States of America, and resident of Cortland, in the county of Cortland, in the State of New York, have invented new and useful Improvements in Folding Tops for Vehicles, of which the following, taken in connection with the accompanying drawings, is a full, clear, and exact description.

This invention relates to certain improvements in folding tops for vehicles commonly known as "one-man-tops" involving the use of a U-shaped frame hinged or pivoted to opposite sides of the body of the vehicle at the rear of the door or doors so as to swing forwardly and rearwardly to and from a substantially vertical position and upon which are supported additional U-shaped frames hinged or pivoted thereto to swing forwardly and rearwardly for receiving and supporting a flexible top which may be readily extended or folded by a single operator without assistance.

In devices of this character it is customary to provide one or more intermediate bow supporting frames between the front bow and main bow and to support said intermediate bow or bows upon the outrigging for the front bow and to mount said outrigging in such manner that it will be concealed at the inner side of the side quarters of the cover when extended for use, but so far as I am aware the members of the outrigging extend along the arm rests some distance beyond the front edge of the seat when the top is crashed thereby obstructing to a greater or less extent the free use of the arm rests, and one of the main objects of my present invention is to remove this objection.

Another object is to enable the intermediate bows to assume more nearly an upright position when the top is extended than has heretofore been practiced.

A further object is to provide simple and efficient means to compensate for any inequalities of adjustment of the strut connections between the main and intermediate bow supporting members and the outrigging for the front bows so as to enable the folding parts to fold and unfold without binding or cramping, and, therefore, with the utmost freedom and ease of action.

Other objects and uses relating to specific parts of the folding top will be brought out in the following description.

In the drawings:

Figure 1 is a side elevation partly broken away and partly in section, of the one-man-top embodying the features of my invention.

Figure 2 is an enlarged elevation partly in section of a portion of the main supporting frame for the cover and outrigging showing one of the compensating devices in the strut connection between said frame and out-rigging.

Figure 3 is an enlarged detail sectional view taken on line 3-3, Figure 1.

Figure 4 is a further enlarged transverse sectional view taken in the plane of line 4-4, Figure 3.

The one-man-top shown is adapted to be mounted upon the body as —A— of a vehicle and comprises a plurality of U-shaped frames —1—, —2—, —3—, and —4— for receiving and supporting a cover —a—, the frame —1— being the main support for the remaining frames and comprising a pair of bow supporting sockets —5—, a bow —6— and suitable clamps or couplings —7— for connecting the ends of the bow to the sockets in a manner hereinafter described.

The sockets or braces —5— are pivoted at —8— to opposite sides of the body —A— to swing forwardly and rearwardly to and from a substantially vertical position as shown in Figure 1.

The frames —2— are similar to the frames —1— except that the sockets —5— are pivoted at —9— to suitable lugs on the lower ends of the sockets —5— while the bows —6— serve to support the rear portion of the top —a—, the latter having its lower edge secured in the usual manner to the rear end of the body of the vehicle.

The frame —3— constitutes what may be termed an outrigging for the front bow —6— having the rear ends of its opposite arms hinged or pivoted at —10— to the inner faces of the couplings —7— and the remaining portions articulated or jointed at —11—, —12— and —13— to form two intermediate sections —14— and opposite end sections —15— and —16—, the joints —11— being arranged to flex upwardly from a horizontal plane but are prevented from flexing downwardly by abutments —17—.

The other two joints —12— and —13— are adapted to flex downwardly from the same horizontal position and are prevented from flexing upwardly by abutments —18— 5 as shown more clearly in Figure 1.

The sections —14—, —15— and —16— are, therefore, hinged together end to end in a substantially straight line and when extended for use are disposed in substantially 10 the same horizontal plane as the pivot —10— which is above the lower edge of the side quarters as —a'— of the cover —a— so that practically the entire outrigger is concealed by the side quarters when extended for use, the said sections exclusive of 15 the bow —6— being of approximately the same or only slightly different lengths so that when the folding parts are clashed to the position shown by dotted lines at the 20 rear of Figure 1, the forward ends of the outrigger will terminate a considerable distance back of the vertical plane of the pivots —8— or back of the rear edge of the seat (not shown) thereby leaving the 25 entire front portions of the arm rests as —b— at opposite sides of the seat free and unobstructed by the folded parts.

The intermediate frame —4— is pivotally mounted upon the outrigger for the front bow —6— preferably coaxial with and upon the pivots —11— which are a sufficient distance forward of the main supporting frame —1— to enable the frame —4— to stand more nearly in a vertical position than has heretofore been practiced which enables the bearing face of the bow —6— to be presented approximately flatwise to the adjacent portion of the cover —a—.

When the top is extended and its bow is 40 attached in the usual manner to the wind shield as B— the cover —a— is placed under tension, and, therefore, exerts more or less downward pressure upon the intermediate frame —4— tending to more firmly lock the 45 hinge joints —11— between the sections —14—.

The opposite bow supporting arms or braces as —19— of the frame —4— are provided with lengthwise channels in their outer faces 50 as shown more clearly in Figures 3 and 4 for receiving the adjacent ends of the bow, said channels serving the same purpose as those in the couplings —7— previously mentioned.

55 In like manner, the opposite arms as —16— of the outrigger may be provided with similar channels for receiving the ends of the corresponding front bow —6—.

Each of the bows —6— is of substantially 60 the same construction as that shown and described in my Patent #1,293,355, Feb. 4th, 1919, and also in my pending applications Serial #128,599 filed Oct. 30th, 1916, allowed Feb. 1st, 1919, and Serial #117,269 filed 65 Aug. 28th, 1916, in that it is composed of a

sheet metal tubular section —20— having a relatively narrow channel in its outer face extending from end to end thereof for receiving a filler —21— of wood or equivalent material into which tacks may be driven for 70 securing the cover —a— to the bow, the inner wall of the channel extending from side to side of the top to brace and reinforce the same, and which also serves to clinch the points of the tacks as they are 75 driven into the wood.

The couplings —7— are similar to those set forth in my pending applications above referred to, in that they constitute longitudinally channeled extensions of the side 80 braces —5— with their channels in their outer faces for receiving the ends of the bow which is additionally secured in the channels by bolts —22— the ends of the bows abutting against the ends of the socks 85 or braces —5—.

The jointed side arms of the outrigger carrying the front bow —6— are adapted to be supported and locked in their extended positions by suitable struts —23—, —24—, 90 and —24'— consisting of relatively small iron rods, the struts —23— having their front ends pivoted at —23'— to the sections —14— a short distance in front of the pivots —12— while their rear ends are pivotally 95 connected at —25— to rocking members —26— on the coupling sections —7— in a manner similar to that shown and described in my pending application #128,599 previously referred to.

100 Each of the struts —23— with its rocking member —26— may be regarded as an articulate strut in which the rocking member —26— serves to compensate for any slight imperfection of adjustment of the folding 105 parts of the outrigger to prevent binding or cramping as the top is folded and unfolded.

The struts —23— are adjusted in such manner that when the top is extended they 110 incline upwardly and rearwardly in a direct line or plane slightly above the joints —12— so as to hold said joints against flexing downwardly.

The struts —24— are pivoted at their rear 115 ends at —27— to the rear sections —15— of the outrigger a short distance from the pivots —12— and inclined upwardly and forwardly therefrom, their front ends being pivoted at —28— to a rocking member 120 —29— on the braces —19— of the intermediate frame —4— to limit the forward rocking movement of the intermediate frame when the top is extended for use.

The struts —24'— are pivoted at —30— 125 to the sections —16— of the outrigger a short distance in front of the pivots —13— and extend upwardly and rearwardly therefrom, their rear ends being pivoted at —31— to the rocking member —29— which serves 130

as a connection between the struts —24— and —24'—, and together with said struts constitute what may be termed articulate connections between the intermediate frame 5 —4— and outrigging for the front bow.

When the top is extended the struts —24— assume their position in a direct line or plane slightly above the axis of the joint —13— to support the joined ends of 10 the sections —16— and —14— in a straight line and to lock said sections in that position.

The object of the rocking members —29— like that of the rocking member —26— is 15 to compensate for any imperfections in adjustment of the folding parts of the outrigging and to enable said parts to fold and unfold freely and easily with a minimum exertion, the struts —23—, —24— and —24'— together with the sections —14—, 20 —15— and —16— constituting an articulate outrigging which is self-locking in its extended position and in addition to the facility in which it may be folded and unfolded causes the parts of the outrigging 25 to terminate some distance back of the arm rests —b— when the top is clashed, and also permits the top to be folded in compact space with the outrigging parts and main frame some distance to the front of the 30 rear edge of the frame —2— so that when enclosed in the usual sheaths the latter will more effectively shed any dust, rain or snow which may tend to accumulate thereon.

In clashing the top from its extended position, the front bow is first released from the wind shield frame —B— and the joint —13— is then flexed downwardly below the line of the struts —24'—, the tension of the cover tending to assist the clashing of the 40 front portion of the cover between the front bow and intermediate bow to the position shown by dotted lines Figure 1. The joint —12— is then flexed downwardly below the plane of the struts —24— whereupon the 45 weight of the outrigging will cause a further clashing thereof to the second dotted position shown in Figure 1 after which the operator simply rocks the main supporting frame —1— with the partially clashed outrigging thereon rearwardly and downwardly 50 to the clashed position shown by dotted lines at the rear of the body.

This construction of outrigging permits the top to be clashed in stages from the front, 55 rearwardly which reduces the extension required to a minimum and assures greater safety from injury to the operator all of which are important factors in folding tops of this character, it being understood by reversing these operations the top may be as easily extended for use.

What I claim is:

1. In a folding top for vehicles, a main 60 bow-supporting member, an outrigging comprising a front bow-supporting section, a

rear section and two intermediate sections, 70 said sections being hinged together end to end, an intermediate bow supporting member hingedly connected to the hinge joint between the intermediate sections, a strut connecting one of the intermediate sections with the main bow-supporting member, and a separate strut connecting the rear section to the intermediate bow-supporting member.

2. In a folding top for vehicles, the combination with a main bow, a four-part articulate out-rigging having an intermediate upwardly flexing joint and downwardly flexing joints at the front and rear of the upwardly flexing joint, the rear part of the 80 out-rigging being hinged to the main bow, an intermediate bow hinged to the out-rigging at a point between the downwardly flexing joints, a strut connecting the main bow with the out-rigging at the rear of the 85 upwardly flexing joint, and a separate strut connecting the intermediate bow with the out-rigging in front of the upwardly flexing joint.

3. In a folding top for vehicles, a main 90 bow-supporting member, an outrigging for the front bow having an upwardly flexing joint, an intermediate bow-supporting member hinged to said joint, and a strut having one end pivoted to the main bow supporting 95 member and its other end pivoted to the outrigging at the rear of the upwardly flexing joint.

4. In a folding top for vehicles, a main bow-supporting member, an outrigging for the 100 front bow having an upwardly flexing joint, an intermediate bow-supporting member hingedly connected to said outrigging at the joint, a strut connecting the intermediate member to said outrigging some distance 105 from the joint and a separate strut connecting the main bow-supporting member to the outrigging at the rear of said joint.

5. In a folding top for vehicles, the combination of a main bow, a four-part articulate out-rigging having an intermediate upwardly flexing joint, and downwardly flexing joint at the front and rear of the upwardly flexing joint, the rear part of the 110 out-rigging being hinged to the main bow, an intermediate bow hinged to the out-rigging between the downwardly flexing joints, connections between the main bow and out-rigging for holding the rear joint against flexing downwardly, and separate connections between the intermediate bow and out-rigging for holding the front joint against flexing downwardly when the top is adjusted 115 for use.

6. In a folding top for vehicles, the combination with a main bow, a four-part articulate out-rigging having an intermediate upwardly flexing joint and downwardly flexing joint at the front and rear of the upwardly flexing joint, the rear part of the out-rig- 120 125 130

ging being hinged to the main bow, an intermediate bow pivoted to the out-rigging between the front and rear joints, separate rocking members on the main bow and intermediate bow, respectively, a strut having one end connected to the rocking member on the main bow and its other end connected to the out-rigging at the rear of the upwardly flexing joint, and a separate strut having one end connected to the rocking member on the intermediate bow and its other end connected to the out-rigging in front of the upwardly flexing joint.

7. In a folding top for vehicles, the combination of a main bow-supporting member, an out-rigging hinged to the main bow-supporting member and provided with a front bow-supporting member, said out-rigging having a downwardly flexing hinged joint, an intermediate bow-supporting member hinged to the out-rigging in front of said joint, a strut having one end pivotally connected to the main bow-supporting member, and its other end pivotally connected to the out-rigging at the front of said joint, and a separate strut having one end pivotally connected to the intermediate bow-supporting member, and its other end pivotally connected to the out-rigging at the rear of said joint.

8. In a folding top for vehicles, the combination of a main bow-supporting member, an out-rigging for the front bow hinged to said member and provided with an upwardly flexing joint and a downwardly flexing joint between its upwardly flexing joint and its pivotal connection with the main bow-supporting member, a strut having one end pivotally connected to the main bow-supporting member, and its other end pivotally connected to the out-rigging at the front of the downwardly flexing joint, an intermediate bow-supporting member hinged to the upwardly flexing joint of the out-rigging, and a separate strut having one end pivotally connected to the intermediate bow-supporting member, and its other end pivotally connected to the out-rigging at the rear of the downwardly flexing joint.

9. In a folding top for vehicles, the combination of a main bow-supporting member, an out-rigging for the front bow hinged to said member and provided with an upwardly flexing joint and downwardly flexing joints

at the front and at the rear of the upwardly flexing joint, an intermediate bow-supporting member hinged to the out-rigging between the downwardly flexing joints, a strut having one end pivotally connected to the intermediate bow-supporting member and its other end pivotally connected to the out-rigging at the rear of the rearmost downwardly flexing joint, and a separate strut having one end pivotally connected to the intermediate bow-supporting member, and its other end pivotally connected to the out-rigging at the front of the foremost downwardly flexing joint.

10. In a folding top for vehicles, the combination of a main bow-supporting member, an outrigging for the front bow hinged to said member and provided with an upwardly flexing joint and downwardly flexing joints at the front and at the rear of the upwardly flexing joint, a strut having one end pivotally connected to the main bow-supporting member, and its other end pivotally connected to the out-rigging at the front of the rearmost downwardly flexing joint, an intermediate bow-supporting member hinged to the upwardly flexing joint of the out-rigging and a separate strut having one end pivotally connected to the intermediate bow-supporting member, and its other end pivotally connected to the out-rigging at the front of the foremost downwardly flexing joint.

11. In a folding top for vehicles, the combination of a main bow-supporting member, an out-rigging for the front bow hinged to said member and provided with an upwardly flexing joint, an intermediate bow-supporting member hinged to said joint, a rocking member mounted on the intermediate bow-supporting member, a strut having one end pivotally connected to said rocking member, and its other end pivotally connected to the out-rigging at the rear of said joint, and a separate strut having one end pivotally connected to the rocking member and its other end pivotally connected to the out-rigging at the front of said joint.

In witness whereof I have hereunto set my hand this 15th day of March 1919.

ALMON W. CURTIS.
